COMBINED CAMPING AND HAULING VEHICLE

George Gordon Davis, Elkhart, Ind., assignor to Trans-Por-Teer Corporation

Filed Feb. 17, 1970, Ser. No. 21,472

Term of patent 14 years

Int. Cl. D12—10

U.S. Cl. D14—3

FIG. 1 is a rear quarter perspective of a combined camping and hauling vehicle embodying the new design; and

FIG. 2 is a front quarter view of the combined camping and hauling vehicle as shown in FIG. 1.

The elements shown in broken lines are included for illustrative purposes only.

I claim:

The ornamental design for a combined camping and hauling vehicle, substantially as shown and described.
